UNITED STATES PATENT OFFICE.

PHILLIP HIEN, OF CHICAGO, ILLINOIS, ASSIGNOR TO DAVID S. WEGG, OF SAME PLACE.

DESIGN FOR A LOCKING-PIN FOR CAR-COUPINGS.

SPECIFICATION forming part of Design No. 33,756, dated December 18, 1900.

Application filed November 24, 1900. Serial No. 37,686. Term of patent 14 years.

To all whom it may concern:

Be it known that I, PHILLIP HIEN, a citizen of the United States, and a resident of Chicago, in the county of Cook and State of Illinois, have invented and produced a new and original Design for a Locking-Pin for Car-Couplers, of which the following is a specification, reference being had to the accompanying drawings, and to the letters of reference marked thereon, which form a part of the same.

In said drawings, Figure 1 is a front elevation of a device embodying my new and improved design. Fig. 2 is a side elevation of the same. Fig. 3 is a rear elevation of the same. Fig. 4 is an elevation of the side opposite that illustrated in Fig. 2. Fig. 5 is a section taken on line 5 5 of Fig. 1. Fig. 6 is a section taken on line 6 6 of Fig. 3.

As shown in said drawings, the leading or material feature of my invention consists of a pin A, provided at its upper end with an enlarged head having on one side of the same an integral downwardly-directed pawl which terminates intermediate of the ends of the pin and is adapted to engage in a movable part in the coupler. At the lower end of the locking-pin, beneath said pawl, is provided a laterally-directed integral projection B'.

Said pin is approximately rectangular in cross-section and on its front and rear sides, respectively, is grooved longitudinally, as indicated in Figs. 1, 3, 5, and 6, thereby greatly reducing the weight of the same, while preserving the strength of the same against lateral strain. Said pawl B is slightly concave on its face adjacent to the end, as indicated in Figs. 1 and 4, and the upper surface of the lateral projection B' is convex longitudinally. The upper end of said pin is provided on each side with a laterally-directed flange, the under surfaces of which lie in a plane and at right angles with the axis of the locking-pin. An eye is provided at the upper extremity of the locking-pin, adapted to afford engagement for a chain or other operating device.

Having described my invention, what I claim as new, and desire to secure by Letters Patent, is—

The design for a locking-pin for car-couplers, substantially as shown and described.

In testimony whereof I have hereunto subscribed my name in the presence of two subscribing witnesses.

PHILLIP HIEN.
